UNITED STATES PATENT OFFICE.

AMOS F. SWEIGART, OF LONGHORNE, PENNSYLVANIA.

SWITCH.

SPECIFICATION forming part of Letters Patent No. 718,229, dated January 13, 1903.

Application filed October 11, 1901. Serial No. 78,380. (No model.)

To all whom it may concern:

Be it known that I, AMOS F. SWEIGART, a citizen of the United States, residing at Longhorne, in the county of Bucks, State of Pennsylvania, have invented certain new and useful Improvements in Switches; and I do hereby declare the following to be a full, clear, and exact description of the invention, such as will enable others skilled in the art to which it appertains to make and use the same.

This invention relates to switches in general, and more particularly to the class of crossover-switches for switching from one to the other of parallel tracks, although the principles involved may be embodied in switches for other specific purposes.

The object of the invention is to provide a switching mechanism which will prevent accidents due to the usual solid frog, a further object of the invention being to provide a construction wherein by the operation of a single lever the several movable rails will be shifted simultaneously into corresponding positions and will be locked in their adjusted positions, whereby guard-rails will be dispensed with and accidents will be avoided.

In the drawings forming a portion of this specification, and in which like numerals of reference indicate similar parts in the several views, Figure 1 is a top plan view showing a complete mechanism embodying the present invention. Fig. 2 is a side elevation of the structure. Fig. 3 is a section on line 3 3 of Fig. 1 and showing the mechanism for throwing a pair of movable rails and the mechanism for operating the locking-bolts. Fig. 4 is an enlarged top plan view with portions of the rails broken away and showing the locking mechanism. Fig. 5 is a section on line 5 5 of Fig. 1. Fig. 6 is a section on line 6 6 of Fig. 1. Fig. 7 is a section on line 7 7 of Fig. 1. Fig. 8 is a perspective view of the switch-stand and the connected ends of the shifting-rods.

Referring now to the drawings, there are shown two trackways, one of which includes the pair of movable rails 10 and 11, while the other includes the pair of movable rails 12 and 13, other rails being disposed at the fixed ends of the movable rails, as usual.

The free ends of the rails 10 and 11 are adapted for movement into operative relation

or registration with the pairs of rails 14 and 16 and 15 and 17, respectively, the rails 14 and 16 being included in the main trackway, 55 while the rails 15 and 17 are fixed crossover-rails.

The free end of the movable rail 12 is adapted to register with the rails 18 and 19, while the free end of the rail 13 is adapted to register 60 with the rails 20 and 21, rails 19 and 21 being main-track rails of the second track, while the rails 18 and 20 are crossover-rails. The rail 18 registers with a fixed crossover-rail 22 adjacent to a main-track rail 23, while the 65 crossover-rail 17 registers with a rail 24 adjacent to a fixed rail 25, the rails 23 and 25 being main-track rails.

The rails 19 and 20 converge, as shown, and form a Y, as do also the rails 24 and 25, the 70 stems of the Y's being toward each other, and between these mutually-adjacent ends is disposed a movable rail 26. Through the rail 26, adjacent to rail 25, is formed a slot 75 through which is passed an arcuate metal plate 27, the ends of which are bent downwardly and secured to a tie 28 of the railway, and between this slot and the end of the rail is formed a perforation through which is 80 passed a rod 29, mounted in ears 30 upon the tie 28, and upon the rod and at each side of the rail is disposed a helical spring 31, so that the rail-section is held pivotally upon the rod. In the opposite end of the rail-section is a 85 transverse slot through which is passed a plate 32, having its ends bent downwardly and secured upon the tie 33, this plate acting as a guide-plate for the rail. Thus when rails 12 and 13 are in registration with rails 19 and 21 and rail-section 26 is in registration with 90 rail 19 the main line is open; but when the rails 12 and 13 are shifted to register with rails 18 and 20 and rail 26 is shifted to register with rail 20 a train may move from rails 12 and 13 to rails 14 and 22. To permit a 95 train to move from rails 14 and 22 to rails 15 and 17, a movable rail 34 is disposed between the pair of converging rails 23 and 22 and the pair of converging rails 15 and 16. The rail 34 is perforated through its end adjacent to rail 22, and through this perforation is engaged a rod 35, mounted in ears 36 upon the tie 37, helical springs 38 being disposed upon the rod at opposite sides of and bearing upon

the rail to hold it yieldably, so that a pivotal mounting is secured. Adjacent to each end of the rail is formed a transverse slot, and through these slots are passed the guide-
5 plates 38' and 39, having their ends bent downwardly and secured to the ties. When the rail 34 is shifted to register with rails 15 and 22, a train upon rails 22 and 24 may pass onto the rails 10 and 11 of the second main track-
10 way. When the rail 34 is shifted to register with rails 16 and 23, the second main track-way, which includes rails 10 and 11, is open through.

It will be noted that the rails 10 and 11 and
15 rails 12 and 13 are securely fastened by cross-
braces 40 and 41, respectively, while they are
limited in their movements by the guide-
plates 42 and 43, which are passed through
20 openings in the rails and have their ends
turned downwardly and secured to adjacent
ties. Furthermore, to hold the rails yield-
ably spaced at their rear portions U-shaped
springs 45 and 46 are provided and have their
25 ends engaged with the rails, while their bights
are engaged with blocks 47 and 48, disposed
between the rails and secured to ties. In
connection with these movable rails there are
provided means for shifting them simultane-
ously into coöperative positions to open both
30 trackways straight through or to open the
crossover and also means for locking the mov-
able rails in their shifted positions.

For shifting the rails a shaft 50 is provided,
which is mounted in bearings in plates 51,
35 secured to suitable supports, and which shaft
is provided at one end with a lever 52 for os-
cillating it, while at intervals of the length
of the shaft are secured upwardly-directed
crank-arms 53, 54, and 55. A lever 56 is piv-
40 oted upon a tie 57, and to one end of this le-
ver is pivoted a connecting-rod, which is piv-
oted in turn to the rail 11, while to the oppo-
site end of the lever is pivoted a connecting-
rod 58, having its outer end turned laterally
45 and engaged with the lever-arm or crank-arm
53, whereby when shaft 50 is oscillated the
movable rails 10 and 11 will be correspond-
ingly thrown.

To throw the movable rails 26 and 34 sim-
50 taneously in opposite directions, either toward
or away from each other, two angular levers 59
and 60 are provided and are mounted for move-
ment in a horizontal plane upon the ends of
corresponding ties. With one arm of the le-
55 ver 59 is connected a rod 61, attached at its
opposite end pivotally to a bolt 62, engaged
with the rail 34, said arm lying parallel with
the rail and having an upwardly-directed
ear 63, with which is pivotally engaged one
60 laterally-turned end of a connecting link or
rod 64, having its opposite laterally-turned
end engaged pivotally through a perforation
in the crank-arm, so that when the shaft 50
is rocked the lever 59 will be moved to throw
65 rail 34. From the second arm of lever 59,
which lies at right angles to the first arm,

there extends a connecting-rod 65, pivoted at
its opposite end to one end of the angular le-
ver 60, lying substantially parallel with said
arm of lever 59, the second arm of lever 60
70 being connected by link or rod 66 with the
rail 26. As the rails are shifted both from
the lever 59 and the levers 59 and 60 move in
opposite directions, the rails will be moved
in opposite directions upon operation of the
75 shaft 50.

To lock the movable rails in their adjusted
positions, sliding bolts are provided. Be-
tween the convergent ends of rails 20 and 21
is disposed a bolt 67, mounted in the bearing-
plate 68, on which the ends of the rails are
secured and having an upwardly-directed
portion 69, which extends up between the
webs of the rails, a second similar bolt 70
being mounted in the bearing-plate 71 under
80 the ends of rails 18 and 19 and having an up-
wardly-directed portion lying between the
webs of said rails. Thus after the rails 12
and 13 have been shifted these bolts may be
drawn outwardly, so that the upwardly-ex-
90 tending portions thereof will lie partly against
the side faces of the rails 13 and 14 to pre-
vent return movement of said rails. To
throw the bolts in and out, a bell-crank lever
95 72 is mounted transversely of and beneath
the rails, the two cranks 73 and 74 thereof
being engaged with perforations in the ends
of the bolts, so that by rocking the bell-crank
lever the bolts will be moved simultaneously.

Bolts 75 and 76 are mounted in the bearing-
plates beneath the convergent ends of rails
14 and 15 and 16 and 17, for movement to lie
100 against the side faces of rails 10 and 11, and
which bolts are connected with the cranks 77
and 78 of a bell-crank lever 79, passed trans-
versely of and beneath the rails.

A bolt 80 is mounted in the plate 81 beneath
the convergent ends of rails 19 and 20 for
movement to lie alternately against opposite
faces of the rail 26 and is connected with the
110 crank 82 of a bell-crank lever disposed trans-
versely beneath the rail. The bell-crank le-
vers all extend laterally and have their end
cranks pivotally connected with a shift-rod
83, with which is also connected the fourth
115 bell-crank lever 84. Lever 84 has its crank
84' connected to a bolt 86, slidably mounted
in plate 87, beneath the convergent ends of
rails 15 and 16, for movement to engage its
upwardly-extending portion with the side
120 faces alternately of the rail 34. The shift-
rod is connected with lever 52 at one end
for movement by it to shift the whole number
of bell-crank levers to move the bolts sim-
taneously either inwardly or outwardly.

With this construction it will be seen that
by operation of a single lever the whole num-
ber of movable rails will be shifted and the
bolts will be actuated to lock the rails in their
shifted positions.

In practice modifications of the specific con-
struction shown may be made and any suit-

able materials and proportions may be used for the various parts of the construction without departing from the spirit of the invention.

What is claimed is—

- 5 1. In a switch mechanism the combination with fixed rails convergently disposed, of movable rails for registration with the first-named rails interchangeably, bearing-plates beneath the convergent ends of the first-named rails, bolts slidably mounted in the bearing-plates and having portions disposed for engagement with the side faces of the movable rails when the bolts are shifted to one position, a rock-shaft having arms connected with the bolts for reciprocating them, a shift-rod connected with the rock-shaft for oscillating it, an angular operating-lever having one end connected with the shift-rod, and a rock-shaft parallel with the shift-rod and having operative connection with the movable rails, said rock-shaft having an upwardly-extending arm engaged with the opposite end of the angular lever from the shift-rod, whereby when the angular lever is operated, the shift-
- 10 25 rod and the last-named rock-shaft will be reciprocated and oscillated respectively.

2. In a switch mechanism, the combination with convergent rails of a switch-tongue pivotally mounted at one end adjacent to the convergent ends of the rails, and means for holding the pivoted end of the switch-tongue yieldably against bodily lateral movement. 30

3. In a switch mechanism the combination with convergent rails, of a switch-tongue, a transverse bolt passed through the switch-tongue at its end adjacent to the convergent rails and on which the switch-tongue is pivotal and laterally slidably, a helical spring upon the bolt at each side of the switch-tongue for holding the tongue yieldably 35 against lateral bodily movement, an arc-shaped guide-plate passed through the switch-tongue and with respect to which the switch-tongue is movable and shifting means connected with the switch-tongue. 40

In testimony whereof I affix my signature in presence of two witnesses.

AMOS F. SWEIGART.
